UNITED STATES PATENT OFFICE.

CLARENCE E. PERRY, OF IRASBURG, VERMONT.

COMPUTING MACHINE.

Application filed June 3, 1922. Serial No. 565,698.

To all whom it may concern:

Be it known that I, CLARENCE E. PERRY, a citizen of the United States, residing at Irasburg, in the county of Orleans and State of Vermont, have invented certain new and useful Improvements in Computing Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to computing machines and has for an object to provide a machine of improved type and mechanical construction whereby mathematical computations of various kinds as occasion may require may be determined from a mere manual setting of the mechanism to correspond to the requirements of the computation.

A further object of the invention is to provide a mechanism embodying a plurality of bands or sheets carried upon rollers, such sheets to have printed thereon mathematical calculations corresponding to and co-acting with numerals or other mathematical designations appearing upon fixed parts of said machine, inter-acting to designate the mathematical result attained by such proximate designations.

The machine which is disclosed in the present application is intended for mathematical calculations of various kinds, such for instance as addition, subtraction, multiplication or division, but all of such mathematical computations are not shown or even indicated on the drawings, it being understood, of course, that the same machine may carry different designations or other machines supplied for other types or kinds of mathematical calculations, the showing in the drawing being merely that of multiplication but without in any way limiting the machine to a mere multiplying apparatus.

The object of the invention is, therefore, to provide a casing having sight openings therethrough in any desired number exposing to view certain sections of movable sheets carrying mathematical designations contiguous to other mathematical designations appearing upon the casing, which, by the

system employed will designate to the user the result of the mathematical computation desired.

A further object of the invention is to provide a mechanism for mathematical calculations embodying a great degree of elasticity of use and range of operation, whereby mathematical calculations extending into very high numerals will be readily and almost instantly exhibited by a mere manual movement of the parts to correspond to some one of the mathematical designations given at the outset.

With these and other objects in view the invention comprises certain novel parts, units, elements, combinations, inter-actions and functions, as disclosed in the drawings, together with mechanical and functional equivalents thereof, as will be hereinafter more fully described and claimed.

In the drawings:

Figure 1 is a view of the machine in front elevation, the mathematical designations being only indicated and not carried out in full even to represent multiplication, to which the particular machine shown is directed;

Figure 2 is a view of the mechanism of the machine shown in front elevation with the casing broken away;

Figure 3 is a top plan view of the mechanism of the machine with the top of the casing broken away;

Figure 4 is a horizontal sectional view taken on line 4—4 of Figure 2;

Figure 5 is an enlarged detail view of one of the sheets as carried about one of the rollers and as seen through one of the sight openings indicating the multiplication of 3 as a multiplier with various multiplicands appearing upon the casing and the results appearing upon the sheet, there being no assurance, however, that the computation as appearing in this figure is accurate;

Figure 6 is a detail view in side elevation of the adjustable stop showing a part of the casing in vertical section and on an enlarged scale, as indicated by line 6—6 of Figure 1;

Figure 7 is an enlarged detail elevation of the indicator and stop, and

Figure 8 is an enlarged detail view of the

sprocket-actuated lugs which engage the movable stop for accurately positioning the numerated sheets.

Like characters of reference indicate corresponding parts throughout the several views.

The computing machine which forms the subject matter of this application may be arranged to indicate a great variety of mathematical calculations by the mere setting of the mechanism at some point to correspond to some given mathematical quantity or numeral. As shown in the drawings the device is indicated as a machine for performing multiplication and the numerals appearing thereon are multiplier, multiplicand and result, but it is to be understood that the machine is equally as capable of performing other mathematical calculations, as, for instance, division, subtraction or addition and not even limited in its scope to performing those four basic processes.

The arrangement of the numerals both upon the traveling sheets which form part of the present invention and upon the stationary casing for other computations than multiplication will be easily and readily understood by a mathematician and an explanation of the use of the device for multiplication will, it is believed, be all that is necessary to a complete and thorough understanding not only of the mechanism but of its manner of use for various mathematical purposes.

The machine comprises a casing 10 having through the front a plurality of sight openings 11. As shown in the drawings five of these sight openings are provided which number will be found a convenient and desirable number, although it will be perfectly apparent that the machine will operate with a greater or less number of sight openings and associated parts with equal facility and that the number of sight openings will be in accordance with the mechanism contained within the casing to be hereinafter more fully described.

Within the casing a plurality of rollers 12 and 13, as the initial rollers, and 12' and 13' carried to any number desired will be mounted preferably upon vertical shafts 14 and 15 and 14' and 15' respectively. The two rollers 12 and 13 are driven by their shafts 14 and 15 through the medium of pinions 16 and 17 respectively, which engage a gear 18 carried upon a trunnion 19, integral or rigid with the gear 18 is a bevelled gear 20 which engages a gear 21 carried upon a stub shaft 22 provided with a hand-wheel 23, preferably nurled to assist in the rotation of the gear 21 and therewith the gears 20 and 18. It will be obvious that as the nurled hand-wheel 23 is rotated through the train of gears just described, the rollers 12 and 13 will also be rotated in either di-

rection as the hand-wheel is moved in one direction or the other.

Upon the rollers 12 and 13 a band or sheet 24 is wound in such manner, as indicated more particularly at Figure 3, that as the direction of the rollers is reversed, the sheet will be wound from one roller to the other and the reverse. The rollers 12' and 13' are likewise provided with similar sheets 24' and the rolling and unrolling of these sheets from their corresponding rollers will be controlled by means of sprocket chains 25 and 26 which pass over sprockets 27 and 28 respectively on the shafts 14 and 15 and corresponding sprockets 27' and 28' on the shafts 14' and 15', so that all of the rollers 12 and 12' operate in synchronism simultaneously with and corresponding to the similar operation of all of the rollers 13 and 13', so that all of the sheets 24 and 24' are simultaneously wound and unwound from corresponding rollers.

As shown more particularly at Figures 1 and 5 these sheets 24 and 24' will be provided with vertical series of numerals 29 and 29' and at the top a numeral 31 which, in the drawing as Figure 3, is the multiplier. Along the casing adjacent to the sight openings are vertical series of numerals 32 and 33 which are the multiplicands. The multiplying of the multiplicand by the multiplier will produce a given result which appears in the vertical series of numerals appearing upon the sheet through the opening immediately under the multiplier. In other words, the series of multiplicands is constant appearing at all times upon the casing, and as shown in the drawing runs from 2 to 200, it being understood, however, that the exact numerals as shown are wholly unimportant to the present invention either as to their exact arrangement or their range and that certain numerals, as for instance units, tens and the like may be omitted as convenience may make desirable and for the conserving of steps without in any way departing from the present invention. While the numerals have been shown also to solve problems in multiplication a mere mathematical re-arrangement and substitution of the numerals will likewise perform other mathematical computations, the numerals themselves, or their arrangement or their sequence or their proximity forming no part of the present invention.

To properly position and maintain the sheets 24 and 24' in taut relation and to provide for the difference in take-up on account of the winding about lesser or greater circumferences yielding tighteners 34 are provided in the form of rollers mounted upon spindles 35 slideable through keepers 36 and having springs 37 for maintaining the proper or desired tension.

It is obvious that with the machine constructed as above described the rotation of the hand-wheel will result in the exposing of multipliers, if the computation be multiplication, from the lowest desired unit, or fractions, as indicated, to such numbers as may be found desirable. It is desirable, however, that some means be provided for readily stopping the rolling of the sheets to exhibit the multiplier desired. For this purpose a stop plate 38 is mounted to slide horizontally and longitudinally of the machine upon guide rods 39. To co-act with this stop plate 38 a sprocket chain 40 is carried over sprockets 41 journaled adjacent the opposite ends of the casing and also passing over idler sprockets 42 intermediate its ends. These idler sprockets are for the purpose of maintaining the proper relation of the different sides of the sprocket chain relative to each other and to the other parts hereinbefore or hereinafter described. One of the shafts 14' carries a sprocket 43 also engaging the sprocket chain 41 so that as the shaft 14' is rotated by the sprocket chain 24, the sprocket 43 will move the sprocket chain 40. As the shaft 14' is rotated in opposite directions it is obvious that the sprocket chain 40 will also be rotated in opposite directions. This sprocket chain 40 carries lugs 44 and 45 positioned to extend outwardly through a slot 46 in the casing and to engage against the stop plate 38, as indicated more particularly at Figure 1.

The stop plate may be moved longitudinally along the rods 39 as hereinbefore mentioned and a scale 47 is provided adjacent the slot 46, said scale being provided with numerals designating the multiplier upon the sheets. The movement of this stop plate longitudinally of the rods 39 to a position upon the scale to correspond with the multiplier and the movement of the sprocket chain 40 to bring the lug 44 into engagement with the stop plate will automatically set the sheets to exhibit the multiplier to correspond to the numeral indicated by the plate. To more conveniently operate the movable stop plate and to read the designations an indicator 48 is employed and the scale 47 is provided with notches 49, the indicator being provided with a lug 50 to engage in said notches, whereupon the indicator will indicate a numeral upon the scale 47, as shown more particularly at Figure 7. This indicator 48 is preferably mounted upon a spring 51 attached to the guide plate 38 and a hand piece 52 provided for releasing the lug 50 from one of the notches 49 so that the stop plate may be readily moved along the rods 39 to the position desired, upon reaching which the release of the hand piece 52 and the action of the spring 51 will insert the lug 50 into the proper notch, so that the indicator 48 will engage the nu-

merals upon the scale 47 to correspond to the multiplier.

As shown in the drawings and as used as a multiplying apparatus, the multiplicand extends to 200 and the result of multiplying any multiplier by 200 will, therefore, be limited to that figure. As indicated on the scale 47 at Figure 1, the multipliers also run from 1 to 200 so that the computation resulting from the use of these ranges would be a maximum of 200 times 200. Means is provided, however, for multiplying greater numerals by the use of the lug 45. To properly distinguish between the lug 44 and the lug 45, the lug 44 carries an index 53 provided in this instance with the numeral 1 visible from the front, whereas the lug 45 is provided with an index 54 provided in this instance with the numeral 2, as indicated in dotted lines in Figure 1, the front of said index not being shown in the drawings.

By rotating the hand-wheel 23 and therewith the several sheets 24 and 24' to move the index 53 in the direction indicated by its arrow at Figure 3, the multiplier will be made available up to 200 being the last numeral upon the scale, as shown at Figure 1. The rods 39 are made of such length, as shown more particularly at Figures 1 and 3, that the stop plate 38 may be moved to the extreme right, permitting the lug 44 and its index 53 to pass through the L-shaped slot 55 at the right-hand end of the machine and simultaneously to permit the lug 45 and its index 54 to pass through the L-shaped slot 56 at the left-hand end of the machine. In this way the sheets 24 and 24' may be advanced through a greater range than is possible by the mere movement of the lug 44 through its range from fractions, or zero, to 200, whereby in a multiplying computation 200 is added to the result and the lug 45 and index 54 will move along as previously described for the lug 44 and index 53. It will be seen, especially from Figure 8, that the index 54 is extended outwardly further than the index 53. The L-shaped slot 56 extends outwardly farther than the L-shaped slot 55, so that in action at zero, the index 53 will engage against the cushion or stop 57 to prevent moving beyond zero in that direction, whereas the index 54 will engage against the cushion or stop 58 to prevent moving that index beyond the maximum limit in that direction. In other words from the position of the lug 44 and index 53 at zero, the device can be moved only in one direction, but may be moved in that direction by the removal of the stop plate 58 from its path of movement to pass through the slot 55, simultaneously bringing into action the index 54 coming outwardly through the slot 56, which will now travel along until it engages

the stop plate 38 which has been adjusted to the addition of 200 to the multiplier. The range of the device is, therefore, not 200 as a maximum multiplier but 400 as a maximum multiplier, it seeming unnecessary to show the different multipliers appearing upon the scale 47 to such maximum amount, although it is to be understood that they may or may not be shown as the preference of the user or maker may make desirable.

In operation, assuming that the computation is to be multiplication and the multiplier 3, the multiplicand any number within 15 in the range from 2 to 200, as disclosed along the margins of the first sight opening, the stop plate 38 will be moved along the rods 39 manually until the indicator 48 reaches the desired multiplier. In the example shown, 3 being the multiplier, the indicator will be stopped at 3 and the lug 50 will enter one of the notches of the scale 47, as indicated more particularly at Figure 7. The handwheel 23 will now be rotated to 20 move the several sheets until the index 53 engages against the stop plate 38, whereupon each of the several sheets will disclose through its respective sight opening the multiplier 3 at the top of the column, as 25 shown at Figures 1 and 5. By referring then to the multiplicands appearing upon the margins of the casing adjacent this sight opening and referring back from this multiplicand to the numeral appearing 30 upon the sheet through the sight opening, the result of such mathematical calculation will be read instantly and accurately. The multiplicands appearing upon the margins of each of the sight openings will be progressive from the lowest, which may be 2, as indicated in the drawings, or may be 35 fractions, as also indicated, to any amount desired, as for instance 1,000, as shown in Figure 1. The result of computing by the 40 use of the index 53 will be, therefore, any multiplier from zero, or a fraction, to 200 multiplied into a multiplicand of any number desired, as for instance 2 to 1,000. By 45 rotating the sprocket chain 40 until the index 54 is brought into sight the multiplier is increased beyond 200 by another similar range, so that the maximum as shown in the numerals in the drawing would be a 50 range of multiplying from 2 or a fraction 55 as a multiplicand to 1,000 multiplied by any multiplier from 2 or a fraction to 400. It is to be understood, however, that even in multiplication the range of the machine is in no way limited either as to scope. 60 range or identity by the numerals indicated and that any range found desirable or found within the scope of the machine or within the necessities of the user is within the scope of the present invention and that 65 the necessary designating numerals upon

the casing, the scale or sheets for other than multiplication will be readily apparent to a mathematician or one skilled in the art and no attempt has been shown here to disclose either this range of numerals and results or indicate the manner of use, as it is believed such use will be perfectly apparent.

What I claim is:

1. A computing machine comprising a casing provided with a plurality of sight openings, a like number of rollers positioned adjacent the sight openings, a similar group of rollers spaced from the said first group of rollers, sheets wound about the pairs of rollers of the two groups and visible in part through each of the sight openings, manual means for rotating the rollers selectively in opposite directions to wind and unwind the sheets upon the rollers, numerical groups positioned upon the casing adjacent the sight openings, other numerical groups positioned upon the traveling sheets and displayed through the sight openings, said groups upon the sheets bearing mathematical relations each to the other, and a stop 50 manually movable and numerically designated adapted to interrupt the movement of the sheets to display numerical groups predetermined by the positioning of the stop.

2. A computing machine comprising a plurality of pairs of rollers, sheets wound upon the rollers, manual means for winding and unwinding the sheets from the rollers to display varying numerical groups, a sprocket chain actuated by the rotation of the rollers and moving in consonance therewith, a sliding stop, a numerical scale adjacent to and co-acting with the sliding stop, and a lug carried by the sprocket chain positioned to engage against the stop and limit 100 the movement of the traveling sheets.

3. A computing machine comprising a plurality of pairs of rollers, a sheet wound upon each of the pairs of rollers and provided with different but mathematically-related groups of numerals, means to rotate the units of the several pairs of rollers in synchronism, a sprocket chain carried by and moving in consonance with the movement of the rollers, a stop adapted to be manually moved and positioned, a lug carried by the sprocket chain positioned to engage against the stop and limit the movement of the sprocket chain to display a group of numerals upon the sheet predetermined by the location of the stop, means facilitating the movement of the stop out of the path of movement of the lug, and a second lug carried by the sprocket chain movable into co-acting position with the stop and determining by its position the displaying of other groups of numerals upon the sheets.

4. A calculating machine comprising a casing having a plurality of sight openings,
